CLAIM

We claim the ornamental design for a vaping device, as shown and described.

DESCRIPTION

FIG. 1 is a perspective view of a front side of a vaping device;

FIG. 2 is a view of a left side of the vaping device;

FIG. 3 is a view of a right side of the vaping device;

FIG. 4 is another perspective view of the front side of the vaping device;

FIG. 5 is a top view of the vaping device;

FIG. 6 is a bottom view of the vaping device; and,

FIG. 7 is a front view of the vaping device.

In the drawings, the claimed design is defined by solid lines and shaded surfaces; dot-dash broken lines represent boundaries of the claim and form no part thereof; all other evenly-spaced broken lines depict unclaimed environmental subject matter only and form no part of the claimed design.
